[57] CLAIM

The ornamental design for an X-ray camera for medical treatment, as shown and described.

DESCRIPTION

FIG. 1 is a front and right side perspective view of an X-ray camera for medical treatment, showing our new design;

FIG. 2 is a front elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a rear elevational view thereof; and,

FIG. 8 is a cross-sectional view, taken along the line 8—8 in FIG. 4 thereof;

FIG. 9 is a cross-sectional view, taken along the line 9—9 in FIG. 2 thereof;

FIG. 10 is a cross-sectional view, taken along the line 10—10 in FIG. 2 thereof; and,

FIG. 11 is a perspective view, on a reduced scale, in use condition; the broken line showing is for illustrative purposes only and forms no part of the claimed design.
